UNITED STATES PATENT OFFICE

96,839

DESIGN FOR A COMBINED FAUCET, SOAP DISH, AND FILTER

William R. Johnston, River Forest, Ill.

Application January 21, 1935, Serial No. 54,986

Term of patent 7 years

To all whom it may concern:

Be it known that I, William R. Johnston, a citizen of the United States, residing at River Forest, in the county of Cook and State of Illinois, have invented a new, original, and ornamental Design for a Combined Faucet, Soap Dish, and Filter of which the following is a specification, reference being had to the accompanying drawing, forming a part therof.

Figure 1 of the drawing is a perspective view of a combined faucet, soap dish, and filter embodying my new design; and

Figure 2 is an end view.

I claim:

The ornamental design for a combined faucet, soap dish, and filter, substantially as shown.

WILLIAM R. JOHNSTON.
